UNITED STATES PATENT OFFICE.

HENDRIK PIETER DEN BOER, OF ROTTERDAM, NETHERLANDS.

STOVE.

Application filed March 20, 1924. Serial No. 700,668.

To all whom it may concern:

Be it known that I, HENDRIK PIETER DEN BOER, subject of the Queen of the Netherlands, residing at Rotterdam, Province of 5 South-Holland, Kingdom of the Netherlands, have invented certain new and useful Improvements in Stoves, of which the following is a specification.

The invention relates to improvements in 10 stoves and more particularly to a stove possessing the advantage, that the heat of the flue-gases is used more economically than in known stoves, so that little heat reaches the chimney and a high efficiency is 15 obtained.

In carrying out the invention the stove is furnished with a core of refractory brick within a shell, said core extending to the bottom of the fire-space, whilst the part 20 above the charge-opening or openings of the stove occupies nearly the whole space within the shell, said part being provided with one or a plurality of parallel passages for the flue-gases. After lighting the fuel the core 25 will accumulate quickly a large quantity of heat, which otherwise would be lost in the chimney. The flue-gases come in contact with the upper part of the core and are obliged to follow the passages in that part 30 before reaching the chimney. In this way all heat generated will be usefully employed, the emission of heat lasting a long time after the fire in the grate has been extinguished.

35 The accompanying drawing illustrates a construction according to the invention.

Fig. 1 is a longitudinal section of the stove.

Fig. 2 is an elevation, whilst Figs. 3 and 40 4 are cross-sections on lines III—III and IV—IV in Fig. 1.

In the construction shown, a core of refractory brick or other suitable material is provided within a shell 3, said core consisting of two parts 1 and 2, the lower part 45 1 having such dimensions that between the shell and the core a space for the fire place is provided. The upper part 2 which is above the charge-openings 4 of the fuel, can have a larger diameter and then extends almost to the shell so as to leave only an annular passage 5. This part of the core

is spaced apart from the shell 3 by refractory bricks 6, the shell 3 further being provided at the lower end with a lining 7 of 55 refractory material. The charge openings 4 are closed by the usual pivoted flaps 4^a.

The usual openings 8 for the discharge of ash are beneath the grate 9^a of the stove, said openings being closed by flaps 8^a. 60

When the fuel burns, the gases produced will first heat the core and being led directly along the outer shell 3 of the stove 65 efficiently heat the surrounding room, before reaching the chimney 9. In the construction shown two openings 9 are shown in order to enable the stove to be joined in two ways to the chimney. Besides leading the flue-gases between the circumference of the upper part 2 of the core and the outer 70 shell 3 of the stove one or more parallel passages may be provided in the core in a longitudinal direction between the spacing bricks 6.

What I claim is:

1. In combination in a stove, a shell having an outlet opening at one end and an inlet at the opposite end, and a continuously solid refractory core within said shell and extending from end to end thereof and so 80 spaced from said shell throughout its entire length as to provide a fire place between said shell and core and a flue leading therefrom to the aforesaid outlet opening.

2. In combination in a stove, a shell having an outlet opening at one end and an inlet opening at the opposite end, said shell being of increased cross-sectional area for a distance around the inlet end, and a continuously solid refractory core concentrically mounted within said shell and extending from end to end thereof, that portion of said core positioned within the enlarged portion of the shell being of considerably decreased cross-sectional area thereby 95 cooperating with the enlarged shell portion to form a fire box; said core being so spaced from said shell throughout its entire length as to provide a continuous surrounding flue leading from the inlet to the outlet end.

In testimony whereof I have hereunto set my hand.

HENDRIK PIETER DEN BOER.
